(57) **CLAIM**

The ornamental design for a capacitor, substantially as shown and described.

DESCRIPTION

FIG. 1 is a front top-left perspective view of a capacitor, showing my new design, taken at line 1 in FIG. 6;

FIG. 2 is a front elevation view thereof, taken at line 2 in FIG. 1;

FIG. 3 is a rear elevation view thereof, taken at line 3 in FIG. 1;

FIG. 4 is a side elevation view thereof, taken at line 4 in FIG. 1;

FIG. 5 is an opposite side elevation view thereof, taken at line 5 in FIG. 1;

FIG. 6 is a top plan view thereof; and,

FIG. 7 is a bottom plan view thereof.

The evenly spaced broken lines depict the bounds of the claimed design and form no part of the claimed design, while all other evenly spaced broken lines are directed to environment and form no part of the claimed design. In addition, the unshaded surface that directly adjoins the claimed solid line edge forms no part of the claimed design. The dot-dash broken lines in FIGS. 1 and 6 are used to identify the orientation of the views, are for reference purposes only, and form no part of the claimed design.
